DESIGN FOR A CARPET.

Design No. 13,680, dated February 27, 1883.

UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 13,680, dated February 27, 1863.
Application filed January 26, 1863. Term of patent 3½ years.

To all whom it may concern:

Be it known that I, PAUL PIGNOT, a citizen of France, and a resident of the city of Yonkers, county of Westchester, and State of New York, have invented or produced a new and original Design for a Pattern to be Inwrought into Moquette and other Carpeting, similar to the photographs accompanying this specification; and I do hereby declare that the photographs accompanying this specification do give and convey to any one skilled in the art of carpet-weaving a defined and thorough description of the nature of my invention, and is sufficient to enable any one skilled in the art of carpet-weaving to use my invention.

What I claim as my invention, and desire to secure by Letters Patent, is—

The design hereunto annexed, when applied to carpeting in the form similar to the photographs accompanying this specification.

PAUL PIGNOT.
